MOBILE DINER

Harry L. Bartholomew, Chicago, Ill., assignor to Indian Trailer Corporation, Chicago, Ill., a corporation of Illinois

Application November 18, 1949, Serial No. 6,117

Term of patent 14 years

(Cl. D14—3)

To all whom it may concern:

Be it known that I, Harry L. Bartholomew, a citizen of the United States and resident of Chicago, in the county of Cook and State of Illinois, have invented a new, original, and ornamental Design for a Mobile Diner, of which the following is a specification, reference being had to the accompanying drawings, forming a part thereof.

Figure 1 is a perspective view of the front side of the mobile diner, viewed from the rear end of the same, the rear side door open, and the rear end door closed.

Figure 2 is a perspective view of the front side of the mobile diner, viewed from the front end, the rear side door being closed.

Figure 3 is a perspective view of the rear side of the mobile diner, viewed from the rear end, the rear end door being open.

The top of the mobile diner is slightly longitudinally curved and such top is substantially transversely flat. The characteristic features of my design reside in the portions shown by means of the full lines in the drawings.

I claim:

The ornamental design for a mobile diner, as shown and described.

HARRY L. BARTHOLOMEW.
